UNITED STATES PATENT OFFICE.

HOWARD M. DUDLEY, OF PHILADELPHIA, PENNSYLVANIA.

DYEING-MACHINE.

1,258,545.

Specification of Letters Patent. Patented Mar. 5, 1918.

Application filed January 11, 1917. Serial No. 141,729.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Other objects of my invention will be evident upon a consideration of my specifications and claims.

I have found that the even or uneven dyeing results obtained in a machine of this general character depend largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if the fiber-mass is supported in the dyeing chamber upon thin strips of metal, or other suitable material, allowing an extreme amount of openings for the passage of the dye-liquor into the fiber. This result can be further augmented if the dye-liquor is forced through passages prior to its introduction into the dyeing chamber.

The device of my invention accomplishes this in an inexpensive and effective manner.

Related forms of my device are shown in the accompanying drawings, in which similar parts are designated by similar numerals.

Figure 1 is a side view of one form of my invention, partly broken away to disclose a portion in cross-section.

Fig. 2 is a cross-section through the line 2-2 of Fig. 1.

Fig. 3 is a side view of one of the sup-

porting members in the fiber-supporting plate.

Fig. 4 is a side view of one of the plates in the liquor supply chamber. 60

Fig. 5 is a side view of a modification of one of the plates in the liquor supply chamber.

Fig. 6 is a side view of a modified form of the supporting members in the fiber-supporting plate. 65

The outer portion of the dyeing machine comprises the cylindrical shell 7 and the cylindrical shell 8, fixedly attached to each other by the bolts 9, 9; the conical shaped shell 10 fixedly attached to the shell 8 by the bolts 11, 11 and the centrifugal pump 12 fixedly attached to the shell 10 by the bolts 13, 13. A fiber-supporting plate 14 is situated between the shells 7 and 8 and comprises the annular member 15 and a series of thin blades or supporting members 16, 16 parallel to each other and fixedly attached to the member 15. These blades or supporting members are as thin as possible and are 80 situated as far apart as possible to correctly hold the material to be dyed, while allowing the maximum of space for the passage of the dye-liquor.

The machine is provided with a removable annular foraminous plate 17, the construction of which is similar to the foraminous plate 14.

An annular angle-shaped member 18, is 90 slidable within the shell 7, capable of abutment upon the plate 17 and maintained in any desired position by means of the thumbscrews 19, 19, which thread within the shoulders 20, 20 fixedly attached to the shell 7.

A series of plates 21, 21 are positioned 95 in the interior portion of the shell 10, the plates extending across the chamber formed by the shell 10 and from the top to the bottom thereof.

A second series of plates 22, 22 are positioned 100 in the chamber of the pump 12 in alignment with those within the chamber of the shell 10, although this series of plates may be omitted if desired.

A perforated steam pipe 25 is introduced 105 into the chamber formed by the shell 8.

In order to facilitate reference to the various chambers, they will hereafter be referred to as the top chamber 26, the dyeing chamber 27, the liquor supply chamber 28, 110 the plate chamber 29, and the pump chamber 30.

An overflow pipe 31 connects the top chamber 26 with a liquor reserve tank 41, which is in turn connected to the centrifugal pump 12, by means of the pipe 42 carrying the valve 43.

A pipe 32 connects the pump 12, with a liquor supply tank, not shown, the pipe 32 carrying the valve 33.

A pipe 34, 35 extends from within the liquor supply chamber 28 to a point above the top chamber 26, and carries a thermometer 36 for regulating the temperature passing through the pipe 34, 35.

A sample dyeing machine 37, exactly similar to the above described dyeing machine, except in smaller proportions, is connected to the liquor supply chamber 28 by the pipe 38 and to the top chamber 26 by the pipe 39. The sample material in the machine 37 is examined by removing the top 40 which is threaded to the sample machine 37.

Fig. 5 illustrates a serrated plate 44, a series of which may replace the plates 21, 21, and Fig. 6 illustrates a double serrated blade 45 which may replace the blades 16, 16.

The operation of the device is as follows:

The annular member 18 and the foraminous plate 17 are removed, the goods to be treated introduced into the dyeing chamber 27, the plate 17 replaced and pressed down upon the goods by means of the member 18. A small quantity of the same goods is placed in the sample device 37. The pump 12 is started and the valve 33 opened, allowing the liquor to flow through the pipe 32 into the pump 12, by which it is forced upwardly through the pump chamber 30, the plate chamber 29, the liquor supply chamber 28, and the goods in the dyeing chamber 27, into the top member 26. When the liquor has reached the over-flow pipe 31, it flows into the reserve tank 41 and from there through the pipe 42 into the pump 12 for continuous circulation. The object of the reserve tank 41 is to allow of the production of a larger quantity of dye-liquor than is necessary to fill the shells 7, 8 and 10. By this means the strength of the dye-liquor may be governed to meet the requirements of each individual dyeing operation, and the liquid maintained in a condition where the dye will not be precipitated upon the fiber, causing uneven results. It also allows a more uniform supply of liquor to the pump 12.

From time to time, the valve 44 is closed, the top 40 is removed for the purpose of examining the condition of the dyeing operation and is then replaced and the valve 44 opened. By this means the condition of the dyeing operation in the dyeing chamber 27 may be judged without stopping the dyeing operation, or breaking off a piece of the fiber contained therein.

It is evident that during this operation the

liquor is forced upwardly between the series of plates 22, 22 and 21, 21, and through the spaces between the blades 16, 16, of the fiber-supporting plate 14 into the fiber contained thereon, blades 16, 16, being so thin that they do not interfere with the uniform distribution of the dye-liquor through the fiber. As the plate 17 is the same as plate 14, the liquor pressure will be maintained within the dyeing chamber 27.

I do not limit myself to the size, shape, number or arrangement of parts as shown and described, all of which may be varied without going beyond the scope of my invention as described and claimed.

What is claimed, is:

1. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates and means for forcing a liquid through the openings in the first plate, the fiber chamber and the openings in the second plate.

2. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates, a liquid supply chamber below the first plate, a plate-containing chamber below the supply chamber, a series of thin plates within the plate-containing chamber so arranged as to allow the passage between them of a liquid from a pump chamber to the supply chamber, a pump chamber and means for forcing a liquid through the receptacle.

3. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates, a series of thin plates below the first foraminous plate, means for forcing a liquid between the series of plates, and means for returning the liquid from the top of the receptacle to the forcing means.

4. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates, a series of thin plates below the first foraminous plate, means for

forcing a liquid between the series of plates, a reserve tank, means for conducting the liquid from the top of the receptacle to the reserve tank, and means for conducting the liquid from the reserve tank to the forcing means.

5. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates, a liquid supply chamber below the first plate, a plate-containing chamber below the supply chamber, a series of thin plates within the plate-containing chamber so arranged as to allow the passage between them of a liquid from a pump chamber to the supply chamber, a pump chamber, a smaller testing device similar and proportionate to, and exterior to, the larger device, means for connecting the spaces below the two fixed foraminous plates to allow of the passage of a liquid and means for forcing a liquid through the two devices.

6. In a dyeing machine, in combination, a receptacle, a foraminous plate comprising a series of thin blades within the receptacle and fixedly attached thereto, a fiber chamber adjacent to the foraminous plate, a smaller testing device similar and proportionate to, and exterior to, the larger device, and means whereby a liquid may be forced proportionately through the two devices.

7. In a dyeing machine, in combination, a receptacle, a foraminous plate comprising a series of thin blades within the receptacle and fixedly attached thereto, a second foraminous plate within the receptacle, means for maintaining the second plate at varying distances from the first plate, a fiber chamber

between the plates, a liquid supply chamber below the first plate, a plate-containing chamber below the supply chamber, a series of thin plates within the plate-containing chamber so arranged as to allow the passage between them of a liquid from a pump chamber to the supply chamber, a pump chamber, a smaller testing device similar and proportionate to, and exterior to, the larger device, means for connecting the spaces below the two fixed foraminous plates to allow of the passage of a liquid and means for forcing a liquid through the two devices.

8. In a dyeing machine in combination, a receptacle, a foraminous plate comprising a series of thin blades within the receptacle and fixedly attached thereto, a second foraminous plate within the receptacle, means for maintaining the second plate at varying distances from the first plate, a fiber chamber between the plates, a series of thin plates below the first foraminous plate, a smaller testing device similar and proportionate to, and exterior to, the larger device, means for connecting the spaces below the two fixed foraminous plates for the passage of a liquid, a reserve tank, means for conducting a liquid from the top of the receptacle to the reserve tank, and means for conducting the liquid from the reserve tank to the liquid forcing means for continuous circulation through the two devices.

Signed at New York city, in the county of New York and State of New York, this 8th day of January, 1917.

HOWARD M. DUDLEY.
